UNITED STATES PATENT OFFICE.

JOHN GUNTHER, OF ST. PAUL, MINNESOTA.

DESIGN FOR A BADGE.

45,378.

Specification for Design.

Patented Mar. 10, 1914.

Application filed January 15, 1914. Serial No. 812,354. Term of patent 7 years.

To all whom it may concern:

Be it known that I, JOHN GUNTHER, a citizen of the United States of America, residing at St. Paul, in the county of Ramsey and State of Minnesota, have invented a new, original, and ornamental Design for Badges, of which the following is a specification.

Reference being had to the accompanying drawing, forming part thereof, the figure is a view of a badge showing my new design.

I claim:

The ornamental design for a badge as shown.

JOHN GUNTHER.

Witnesses:

CHARLES E. CHAPEL,
WILLIAM M. TRCZIYUHN.
